UNITED STATES PATENT OFFICE.

GEORGE HERING, OF LARCHMONT, NEW YORK.

ORE-SEPARATOR.

1,216,118.

Specification of Letters Patent. Patented Feb. 13, 1917.

Application filed July 6, 1916. Serial No. 107,731.

To all whom it may concern:

Be it known that I, GEORGE HERING, a citizen of the United States, and a resident of Larchmont, in the county of Westchester and State of New York, have invented a new and Improved Ore-Separator, of which the following is a full, clear, and exact description.

This invention relates to ore separators and has particular reference to means for recovering or saving the minutest particles of gold and other precious metals which commonly accompany auriferous sands or dust.

15 Among the objects of the invention, therefore, is to provide a simple and efficient machine including a rotary device upon which the ores are received and separated as to size, weight or quality, the action being dependent upon the effect of gravity, adhesion, and in some particulars upon centrifugal force and magnetism.

Another object of the invention is to provide a means requiring a minimum amount 25 of power for effecting the separation contemplated.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical longitudinal section of a preferred embodiment of the invention;

40 Fig. 2 is a vertical transverse section substantially on the broken line 2—2 of Fig. 1;

Fig. 3 is a front elevation, partly broken away, of the delivery mechanism for magnetic ores; and

45 Fig. 4 is a vertical transverse sectional detail on the line 4—4 of Fig. 2.

Referring now more particularly to the drawings, I show a frame including front and rear standards 10 and 11 suitably supported upon a base 12. These parts may be constructed in any suitable manner to provide ample strength and stability for the operating parts of the machine which are supported thereon or journaled therein. A power shaft 13 is journaled in a horizontal

position in said standards and carries a driving element 14 of any suitable nature, but characterized as a belt pulley.

The principal element of the separator is what I term a drum 15, which includes a series of coaxial frusto-conical elements, but which for convenience of description, I will hereinafter designate as cones, and shown in this instance as being five in number, numbered respectively 16 to 20. Each cone is connected by rigid brackets 21 to the next adjacent cone whereby the several cones are held in fixed relation to one another throughout the drum. A series of spider arms 22 extend inwardly to a hub 23 from the brackets connecting the cones 18 and 19. Said hub is rigidly secured to the upper end of a hollow shaft 24 having a long bearing 25 in the upper end of the standard 11. A spider 26 also is formed at the central portion of the cone 20 through which it is rigidly connected to the middle portion of the hollow shaft 24. As illustrated, the axis of the shaft 24 is inclined at an angle of about thirty-eight degrees to the horizontal, but as to this angle I do not wish to be unnecessarily limited since it and other details are subject to a wide range of variation depending very largely, however, upon the inclination of the geometric elements of the several cones.

At the upper end of the standard 10 is secured a hopper 27 into which the material to be separated is dumped in a perfectly dry state. The bottom 28 of the hopper has an outlet leading into the upper end of a rotary delivery spout 29 journaled in a bearing 30 on the standard and also in a bracket 31 secured to the rear face of the standard 10. The spout 29 is rotated at a comparatively low speed from the power shaft 13 through pairs of miter gears 32 and 33, typifying any suitable positive operative connections. The lower end of the spout 29, through the combined action of gravitation and rotation of the spout, delivers the material in moderate quantities upon the inner surface of the first cone 16 not far below the inner edge thereof and below the axis of the drum.

105 All of the geometric elements of all of the cones are straight, but not all of them are arranged in the different cones at the same inclination. For instance, the cone 16 has the greatest altitude or, in other words, has 110

the sharpest pitch. The next two cones 17 and 18 are of the same diameter as the first, but have progressively less pitch or altitude. The last two cones 19 and 20 are progressively smaller in diameter than the first three cones, and are indicated in this instance as having an inclination substantially the same as that of the middle cone 18. Since the diameters of the last two cones are progressively smaller than the first three cones, the effect of centrifugal force on the material received thereupon is taken into account.

With reference to the separation of the fine gold dust from the heavier and coarser particles of sand, gravel, dirt dust or the like, the operation of the machine may be briefly described as follows: With the drum rotated as indicated in the drawings at a low speed around the axis of the supporting shaft 24, and the material to be separated being delivered upon the upper surface of the lower half of the first cone 16, the largest and the coarsest particles of the material will be delivered immediately by gravitation downwardly into a receiver 34 having a mouth projecting beneath the periphery of the cone 16 through approximately one-quarter of its rotation. All the balance of the material will be carried upwardly and inwardly by the inner surface of the cone 16 due largely to adhesion between the same and the cone. As shown best in Fig. 1, it will be noted that that element of the cone 16 at the point where the material is received from the spout 29 is inclined downwardly and outwardly toward the receiver 34, but as such element is carried around with the drum it approaches a horizontal position and then approaches and even passes a vertical position, as indicated at the top of Fig. 1, and thereafter it returns again to its outwardly inclined position at the receiving point. With respect to the material just referred to, all particles will be delivered from the inner surface of the cone 16 during the circuit thereof from the receiving point to the top of the drum. After the coarsest particles are delivered directly to the receiver 34, the next finer portion of the mixture will be delivered inwardly over the inner edge of the cone 16, either directly upon the inner edge of the next cone 17 or into a spout 35, shown in Fig. 2, having an elongated mouth lying along the second quarter of the movement of the cone 16. The lower end of the spout delivers the material received therein upon the lower portion of the cone 17, as shown in Fig. 1, where the same will be treated in a manner corresponding to the treatment of the first material upon the first cone, the coarser particles thereof passing directly by gravity into a receiver 36, and the next grade being carried up and delivered either upon the cone 18 or into the second inwardly located

spout 37, similar to and just below the spout 35, the action of which is similar to that described. The coarser particles from the spout 37 or otherwise received upon the inner surface of the cone 18 are delivered directly downwardly by gravity into the receiver 38, while the finer particles therefrom are delivered directly upon the inwardly projecting smaller cone 19. From this cone, the coarser particles received are delivered into a receiver 39 and the other portions are delivered in turn upon the innermost and smallest cone 20 for a further separation, the larger particles going into a receiver 40, while the finest and richest of the gold dust is delivered finally from the cone 20 through the spider 26 into a receiver 41. In this connection it will be observed that while the inclination of corresponding elements of adjacent innermost cones is the same, the force of adhesion incident to the innermost cone is neutralized to a less extent by centrifugal force, and therefore complete delivery of all of the material will be effected from the last mentioned cone 20 at its top.

In treating certain species of ores I find it advantageous to form upon the inner surface of the cone 16, a series of offsets 42, shown in detail in Fig. 4. The advancing sides of each of these offsets is rounded whereby portions of the material may glide thereover and strike against a baffle plate 43 secured to, but spaced upwardly at its lower edge from the surface of the cones just below or in the rear of the offset 42. The impact of the coarser particles against the baffle plate 43 has a tendency also to agitate the material and facilitate the further separation.

In the treatment of iron ores rich in gold or in which particles of magnetic ores are laden more or less richly with the finest character of gold dust commonly otherwise lost, I find it commercially of great advantage to secure a series of loadstones or magnets to the outer surface of the cone 16. These magnets are indicated at 44 and are arranged as closely together around the outer surface of the cone as may be desired. Each of the magnets is held in a pocket and slightly spaced from the outer surface of the cone 16 whereby a plate of magnetic sheet metal 45 held in a stationary position by a bracket 46, or its equivalent, at the top of the drum will have the effect of neutralizing the magnetism, and thereby any magnetic particles of auriferous ore that will be received upon the inner surface of the cone 16 and carried by the magnets around to the top thereof, will be delivered by gravity directly into a receiver 47, and thence conveyed rearwardly and downwardly through the inclined hollow shaft 24 into a receiver 48. It will be understood that the drum is rotated from the power shaft 13 through bevel

eled gears 49. The attraction of the auriferous magnetic ore to the locality of the magnets is augmented by the action of the offsets and baffle plates 42 and 43.

5 I claim:

1. The herein described ore separator comprising in combination a drum including a series of coaxial cone members, means to connect the several cone members each to each 10 and maintain them in a definite relation to one another, a central rotating supporting shaft for the drum inclined at an acute angle to the horizontal whereby the portions of the cone members at different points are differently inclined to the vertical, means to deliver material to be separated upon one of the cone members at its lower portion, and means to rotate the drum so as to cause the coarser particles of the material received 15 upon each cone member to be separated and delivered outwardly, while the finer particles are delivered inwardly upon the next succeeding cone member for further subdivisions.
2. In an ore separator, the combination of a main frame, power devices journaled in said frame, a shaft journaled in the frame at an acute angle to the horizontal, means to rotate the inclined shaft from the power devices, and a separating drum secured to and rotated at low speed from said inclined 20
- 30

shaft, said drum including a plurality of frusto-conical members of the same diameter but having sides at different inclinations.

3. The herein described drum for an ore 35 separator comprising a series of frusto-conical members arranged coaxially, certain of said members having bases of equal diameter and central openings of equal diameter but having different inclinations. 40

4. The herein described drum for ore separators comprising a series of hollow truncated cones arranged coaxially, a central hollow shaft whose axis coincides with the axis of the drum, cone members, power means 45 acting through the hollow shaft to rotate the drum at a low speed, means to deliver material to be separated upon one of the cone members whence the largest particles are delivered outwardly and the remaining particles delivered inwardly toward the next cone members for further subdivisions, a series of receivers to receive the material from the lower portions of the several cone members, a receiver at the upper portion of the 50 drum to receive material from the top of the drum and deliver the same downwardly through the hollow shaft, and means carried by the first cone member to cause certain portions of the material to be carried up to 55 be delivered into the last mentioned receiver. 60

GEORGE HERING.
